(57) **CLAIM**

The ornamental design for a cushion material, as shown and described.

DESCRIPTION

FIG. 1 is a front view of a cushion material of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof

FIG. 8 is an enlarged view thereof defined by the line 8-8 and 801-801 in FIG. 3;

FIG. 9 is an enlarged view thereof defined by line 9-9 in FIG. 8;

FIG. 10 is an enlarged sectional view thereof taken along the line 10-10 in FIG. 8;

FIG. 11 is an enlarged sectional view thereof taken along the line 11-11 in FIG. 8;

FIG. 12 is an enlarged sectional view thereof taken along the line 12-12 in FIG. 8; and,

FIG. 13 is an enlarged perspective view thereof from the direction 13 in FIG. 8.

The alternate long and short dash lines are the indicator arrow lines and form no part of the claimed design.

1 Claim, 13 Drawing Sheets
